(57) **CLAIM**

The ornamental design for a winch, as shown and described.

DESCRIPTION

FIG. 1 is a front perspective view of a winch showing our new design.

FIG. 2 is a front view of the winch of FIG. 1.

FIG. 3 is a back view of the winch of FIG. 1.

FIG. 4 is a left-side view of the winch of FIG. 1.

FIG. 5 is a right-side view of the winch of FIG. 1.

FIG. 6 is a top view of the winch of FIG. 1; and,

FIG. 7 is a bottom view of the winch of FIG. 1.

The broken lines in FIG. 1 through 7 are included for the purpose of showing portions of the winch which are not part of the claimed design.

1 Claim, 6 Drawing SheetsFIG. 1

FIG. 2

FIG. 3

FIG. 5

FIG. 4

FIG. 6

FIG. 7
